UNITED STATES PATENT OFFICE

2,339,785

PRINTING TELEGRAPH APPARATUS

Ross A. Lake, Oak Park, Ill., assignor to Tele-type Corporation, Chicago, Ill., a corporation of Delaware.

Application November 28, 1941, Serial No. 420,802

16 Claims. (Cl. 197—71)

This invention relates to printing telegraph apparatus and more particularly to case shifting instrumentalities therefor.

In printing telegraph apparatus during printing operations, it is necessary at times to shift the printing platen from one position to another depending on whether it is desired to operate the machine in the letters or lower case position or the figures or upper case position. A printer of the type with which the present invention is concerned is shown in Patent No. 2,225,794 to Ross A. Lake, September 16, 1941.

In prior shifting mechanisms, it had been the practice, as in the Lake patent referred to above, to employ a tensioned spring for shifting the platen from one of its case positions to the other and to reset the springs while shifting the platen to its other case position. This latter shifting operation was accomplished through a linkage system on the working stroke of the bail plunger during the printing operation and it reduced the effectiveness of the bail plunger spring for the achievement of its function of operating the type bars. The operation of the bail plunger and the selection of the pull bars is shown in detail in the Patent No. 1,745,633 to S. Morton et al., granted February 4, 1930.

An object of the present invention is to provide a positive shift mechanism for a platen which will assure that the platen is positively shifted to both its upper and lower case positions.

Another object of this invention is to assure that the platen carriage assumes its case positions when shifted prior to the impingement of the type head upon the paper.

A further object of the invention is to provide means whereby the platen shifts to its proper position so that a full printing impression will be printed on the tape.

Another object of the present invention is to provide reset means for a latching lever of a shifting mechanism whereby minimum strain is placed on the letters pull bar when it is operated to shift the platen.

In the following description, the use of "rear" or "letters" position of the platen designates the lower case position, whereas the use of "front" or "figures" position designates the upper case position of the platen.

In carrying out the present invention, provision is made for shifting the platen from its rear or letters position to its front or figures position by placing the platen carriage under the tension of a spring, one end of which is connected to the platen carriage and the other end

of which is connected to an arm of a U-shaped lever. The U-shaped lever, by means of another spring, is also employed to shift the platen carriage to its rear position. An extension on the bail plunger resets the U-shaped lever when the plunger makes its downward or idle stroke by means of an intermediate lever which engages a depending portion of the U-shaped lever. There is also employed a latching lever in conjunction with the U-shaped lever operable by the letters pull bar to release the U-shaped lever and to allow it to pivot rearwardly under the influence of a spring and thereby drive the platen carriage to its rear or letters position. It can be seen that by the present invention two independently acting springs are employed to provide the power for the shifting operations.

When the bail plunger is in its lower position, its extension rests on the intermediate lever and holds the U-shaped lever in its forward position so that in order to unlatch the U-shaped lever, the bail plunger must rise so that its extension is removed from the path of the rear arm of the intermediate lever in order that the U-shaped lever can pivot towards the rear under the influence of the spring and the letters pull bar must subsequently operate to trip its latching lever which is in engagement with the U-shaped lever.

In operation, the bail plunger moves approximately one third of its upward stroke before the bail engages a pull bar so that by the time the letters pull bar is actuated the extension of the bail plunger has moved clear of the intermediate lever and the U-shaped lever is free to pivot rearwardly under the influence of the spring if the letters pull bar is actuated to release the latching lever of the U-shaped lever.

It should be particularly noticed that the resetting of the U-shaped lever takes place on the downward or idle stroke of the bail plunger while in previous shifting mechanisms the letters pull bar operated on the working or upward stroke of the bail plunger to move the platen carriage to its rear position against the influence of the spring. As previously explained, this placed an undesirable load upon the bail plunger spring. Inasmuch as the idle stroke of the bail plunger is now used to reset the U-shaped lever, the load placed upon the working stroke of the bail plunger is kept to a minimum. As shown in the Morton et al. patent already referred to, the bail plunger on its downward or idle stroke is operated by means of the cam on the main driving shaft and thus, the main drive is now used to

obtain power for the resetting operation whereas in previous practice the upward or working stroke was employed and thus detracted from the power of the spring which operates the bail plunger in its upward stroke. It therefore readily appears that the letters pull bar, as used in the present invention, in addition to operating its type lever merely acts to trip a latching lever and places little additional load upon the bail plunger in its upward stroke.

A more complete understanding of the foregoing objects and features of the invention may be had from the following description when taken in conjunction with the accompanying drawing, wherein,

Fig. 1 is a plan view of the platen shifting mechanism with portions broken away in order more clearly to disclose the apparatus;

Fig. 2 is a front elevation of Fig. 1; and

Fig. 3 is a side elevation of the shifting mechanism.

Referring to the drawing, a suitable base for the platen carriage is shown at 4. Mounted thereon is a frame 5 which has disposed between its front and rear portions a plurality of rods 6 upon which is slidably mounted the platen carriage 7 upon which is carried a platen 8. Attached to the rear of the platen carriage at 9 is a spring 10, the other end of which is attached to arm 11 of a U-shaped lever 12. When the platen carriage is in its rear position, notched portion 13 (Fig. 2) of the vertically extending rear member 14 of the platen carriage is latched up in notch 15 of a rockable latching lever 16 mounted on a pivot 17 and urged to rotate in a clockwise direction, as viewed in Fig. 2, by means of a spring 18. The latching lever 16 has positioned thereunder at its right end, as viewed in Fig. 2, a hooked portion 19 of pull bar 20. Pull bar 20 is the figures pull bar and is moved upwardly by the printing bail when it is selected by the code bars 21 under the control of a selector magnet 2, and trips the latching lever 16 by rotating it in a counterclockwise direction to thereby disengage its notched portion 15 from notched portion 13 of the vertically extending member 14 and allow the platen carriage to slide on the rods 6 to its front or figures position under the influence of the spring 10 which then retracts. The frontward movement of the platen carriage is limited by an adjustable screw 22 mounted on the front vertical member 23 of the platen carriage frame 5.

At the left side of the apparatus, as viewed in Fig. 2, is mounted the mechanism for shifting the carriage from its front or figures position to its rear or letters position. Suitably mounted on pivot 24 (Fig. 3) is the U-shaped lever 12 having upwardly extending arms 11 and 25, a frontwardly depending arm 26 and also a rearwardly extending arm 27. The U-shaped lever 12 is biased to its counterclockwise position by means of a spring 28 which is extended from a frame 29 to arm 25.

When U-shaped lever 12 tilts to its rearward or counterclockwise position under the influence of spring 28, projecting portion 30, of arm 11 of the U-shaped lever, engages the adjustable leg 31 mounted at the top of the platen carriage and thus drives the platen carriage to its rearward position on rods 6.

At the rear of U-shaped lever 12 is an intermediate lever 32, pivoted on shaft 33 which is mounted on frame 29, and having its front end 34 in abutting engagement with the rearwardly

extending arm 27 of the U-shaped lever 12. At the rear end of the intermediate lever 32 is mounted an adjustable screw 35 which is in abutting engagement with the extension 36 of bail plunger 37. The bail plunger 37, as shown in Fig. 3, is in its lower position which it assumes after it has completed its downward or idle stroke. At the left side of the U-shaped lever 12, as viewed in Fig. 2, is mounted a latching lever 38 pivoted on shaft 39 and normally urged to rotate in a counterclockwise direction by means of a spring 40. When the U-shaped lever 12 is in its clockwise position (as shown in Fig. 3) the end portion of arm 41 of latching lever 38 is in engagement with notch 42 of arm 25 of the U-shaped lever. It can thus be seen that both the intermediate lever 32 and the latching lever 38 hold the U-shaped lever 12 in its clockwise position as shown in Fig. 3. At the left side of the code bars 21 is shown a letters pull bar 43 and a space pull bar 44. Either pull bar 43 or 44 is operable to trip the latching lever 38 but, for the purpose of describing the present invention, only the letters pull bar 43 will be referred to.

In operation, when the bail plunger 37 moves upwardly, it removes its extension 36 from contact with the adjustable screw 35 of the intermediate lever 32 which then becomes free to rotate and therefore to remove its arm 34 from blocking engagement with arm 27 of the U-shaped lever 12. The bail plunger 37 moves approximately one third of its upward stroke before the bail engages the selected pull bar so that by the time the letters pull bar 43 is actuated, the front arm 34 of the intermediate lever 32 is no longer in blocking engagement with arm 27 of the U-shaped lever 12. As the pull bar 43 moves upwardly its hooked portion 45 engages the extending portion 46 of latching lever 38. The engagement of pull bar 43 by means of its hook portion 45 with the extending portion 46 of the latching lever 38, causes the latching lever 38 to rotate in a clockwise direction as viewed in Fig. 2. The end portion of arm 41 of lever 38 is thus removed from the notch 42 of the U-shaped lever 12 which is therefore free to pivot rearwardly under the influence of spring 28. When this movement occurs, the projecting portion 30 of arm 11 of the U-shaped lever 12 engages the adjustable leg 31 of the platen carriage 7 to drive it to its rear position as shown in dotted lines in Fig. 3, where the notch 13 of the vertically extending member 14 of the carriage latches in notch 15 of latching lever 16.

The extension 36 of the bail plunger 37 acts to reset the U-shaped lever 12 to its clockwise position when the bail plunger returns downward on its idle stroke after the platen carriage 7 has been thus shifted to the rear. As the bail plunger 37 moves downwardly, its extension 36 again engages the screw 35 to tilt the intermediate lever 32 in a counterclockwise direction. This causes the engagement of the arm 34 of said intermediate lever with the arm 27 of the U-shaped lever 12 which causes the rotation of said U-shaped lever in a clockwise direction against the influence of springs 10 and 28. As the U-shaped lever is rotated to its full clockwise position, its notched portion 42 again latches up upon the arm 41 of the latching lever 38. To limit the rotation of the U-shaped lever 12 in a counterclockwise direction, as viewed in Fig. 3, an adjustable screw 50 is provided which cooperates with the frontwardly extending arm 26 of the U-shaped lever 12 when said U-shaped

lever rotates in a counterclockwise direction, as viewed in Fig. 3. Thus, it will be observed that when the platen carriage 7 is latched in its rear position by lever 16, the resetting operation of the U-shaped lever 12 to its clockwise position (as viewed in Fig. 3) acts to stretch both spring 28 and spring 10, so that spring 10 is distended and is ready for another shifting operation while spring 28 is also distended and ready for its next shifting operation. It should be remembered that when the platen carriage was shifted to its front or figures position, spring 10 became retracted and that during the subsequent shifting of the platen carriage to its rear or letters position, spring 28 operated entirely independent of spring 10.

As shown in Fig. 3, when the U-shaped lever 12 is in its clockwise position, a clearance 47 is provided between the projecting portion 30 of arm 11 of said U-shaped lever and the adjustable depending leg 31 of the platen carriage frame 7. When the platen carriage 7 is in its rear position, shown in dotted lines, a similar clearance 48 is provided. A clearance 60 is also shown between the arm 41 of lever 38 and the notched portion 42 of arm 25 of U-shaped lever 12. When the platen carriage 7 is in its front position, shown in full lines in Fig. 1, the clearance 47 is provided because while this front position is maintained during printing operations, the bail plunger is continually moving up and down, and on its upward strokes its extension 36 exerts no pressure on the intermediate lever 32 so that there is a tendency of the spring 28 to pivot the U-shaped lever 12 rearwardly because when the bail plunger extension 36 rises off the screw 35 the intermediate lever 32 no longer acts to hold the U-shaped lever 12 in its clockwise position although it may still be held in this position by means of the engagement of arm 41 of the intermediate lever 38 with notch 42 of arm 25 of the U-shaped lever. Therefore, if the extending portion 30 of the U-shaped lever 12 was in direct contact with the depending leg 31 without clearance, the tendency of the U-shaped lever to pivot would cause a vibration of the platen carriage 7. Now, as the U-shaped lever 12 tends to rock backwardly, the rocking motion is taken up by the clearance 47 and also by the clearance 60 at the notched portion 42 of arm 24 of the U-shaped lever. The clearance 60 is of such dimensions that notch 42 of arm 25 of the U-shaped lever 12 will engage the end portion of arm 41 and resist further tilting movement of the U-shaped lever. However, the clearance 47 is such that a very slight clearance still remains between the depending leg 31 and the projecting portion 30 of the U-shaped lever 12 so that there is no danger of the projecting portion 30 striking the carriage leg 31 and causing a vibration of the platen carriage 7. It can thus be seen that although the bail plunger extension 36 rises above the intermediate lever 32 on each upward stroke, the slight rocking motion is taken care of by the clearances.

One purpose of providing the clearance 48, as shown in the dotted line positions in Fig. 3, is to allow the platen carriage 7 to travel the last fraction of its rearward movement under the momentum which was built up while the projection 30 on arm 25 of the U-shaped lever 12 was in contact with the leg 31 of the platen carriage 7 and sliding it rearwardly. As the platen carriage 7 approaches the limit of its rearward

movement, the forwardly depending arm 26 of the U-shaped lever 12 engages with the screw 50 mounted on an extension 51 of the platen carriage frame 5, and is thereby prevented from further movement. However, the platen carriage leg 31 is separated from the portion 30 of the U-shaped lever 12 so that the platen carriage 7 moves the remaining portion of its backward travel under momentum and is slowed up because during this last portion of its movement, the platen carriage is not positively driven. This will insure that the platen carriage 7, through the notched portion 13 of member 14, will immediately latch up on the notched portion 15 of latching lever 16 when the platen carriage is driven towards its rear position. In this way, the overtraveling of the platen carriage too far past the notch 15 of the latching lever 16, is prevented and the platen carriage, after its rearward movement, will assume its exact printing position. The platen 8, thus, will be in the proper position to receive the impingement of the typing lever which acts by striking an inking ribbon to print an impression upon a movable tape.

A further advantage of the clearance 48, as shown in the dotted lines in Fig. 3, will now be explained. If the platen carriage 7 has assumed its rearward position, it sometimes happens that during the course of printing operations pull bars 43 or 44 might be actuated when either the letters combination or the space combination impulses are received. Inasmuch as the platen carriage is already in its rearward position, it is important that the operation of either of these pull bars produces no effect upon the platen carriage. When either of these pull bars is operated, as previously explained, U-shaped lever 12 will tilt to its counterclockwise position and if no clearance were provided at 47 then the extension 30, on the U-shaped lever 12, would push against the adjustable leg 31 of the platen carriage 7 when the U-shaped lever 12 moves to its counterclockwise position. This would cause an undesirable vibration of the platen carriage 7 if clearance 48 was not provided.

By the present invention, therefore, the letters and figures pull bars each merely act to trip a latch to perform their respective shifting operations and the resetting of the springs by means of which the power for the shifting operations is provided, is accomplished on the downward or idle stroke of the bail plunger. Thus, little additional load is placed on the operation of the pull bars when they trip their respective latching levers.

As already has been pointed out, when the bail plunger is making its downward or idle stroke, it is receiving its motion from the main drive shaft so that the main drive shaft actually is furnishing the power for the resetting operation of the U-shaped lever. When the bail plunger moves upwardly, however, it receives its power from a return spring which rocks a bell crank lever which moves the bail plunger upward to perform its working operation by means of the usual bail bar to select a pull bar lever determined by the position of the code bars. Therefore, by the present invention, little additional load is placed on the bell crank return spring inasmuch as both the letters and figures pull bars now perform only a light tripping operation as they move upward to actuate their associated type levers to perform the printing operations.

It can thus be seen that through the present

invention a very efficient shift mechanism for platen carriages is employed and by the provision of separate latching levers and separate springs, the independent operation of the shift mechanism, from one position to another, is provided for. The use of separate springs makes it possible to adjust each spring individually without the adjusted spring having any effect upon the shifting operation with which it is not connected.

Various changes may be made in the design of the construction described in the specification without departing from the spirit and scope of the invention.

What is claimed is:

1. In a platen shifting mechanism, a frame, a platen carriage slidably movable on said frame to an upper or lower case position, spring means for driving said carriage to its upper case position, a second independently acting spring means to drive said carriage to its lower case position, and means to simultaneously reset each of said spring means for further shifting operations.

2. In a platen shifting mechanism, a mounting, a platen movable on said mounting to different case positions, driving means for driving said platen to one case position, a second driving means to drive said platen to its other case position, and means to simultaneously reset each of said driving means for further shifting operations.

3. In a platen shifting device, a mounting, a platen movable on said mounting to different operating positions, driving means for driving said platen to one position, means restraining said driving means from actuation, means to release said restraining means to thereby release said driving means to move said platen to one operating position, a second driving means for driving said platen to a second operating position, means restraining said second driving means from actuation, means to release said second mentioned restraining means to cause said second driving means to move said platen to a second operating position, and means to reset both of said driving means for further shifting operations.

4. In telegraph printing apparatus, a bail plunger operable on its working stroke to an upper position and operable on its idle stroke to a lower position, a platen shifting mechanism comprising a frame, a platen carriage slidably mounted on said frame and movable to an upper or lower case position, spring means for driving said carriage to its upper case position, a second independently acting spring means to drive said carriage to its lower case position, resetting means for each of said spring means, and means connected with said bail plunger to operate said resetting means on the downward or idle stroke of said bail plunger.

5. In a platen shifting mechanism, a frame, a platen carriage shiftable on said frame, spring means for shifting said carriage to an upper case position, a second spring means for shifting said carriage to a lower case position, means to hold said carriage in a lower case position against the influence of said first mentioned spring means, means to release said holding means to cause actuation of said first mentioned spring means to thereby shift said carriage to an upper case position, means restraining said second spring means from operation, means to release said restraining means to cause said second mentioned spring means to shift said carriage to a lower case position, and means to reset both spring means for further shifting operations.

6. In a platen shifting mechanism, a mounting, a platen carriage movable on said mounting to a front and rear position, a pivotable lever in the path of but out of contact with said platen carriage, a spring urging said pivotable lever to pivot, holding means for said pivotable lever, means to release said holding means to enable said pivotable lever to pivot under the influence of said spring and contact said platen carriage to drive said platen carriage to its rear position, means for latching said platen carriage in its rear position, and means to stop the movement of said pivotable lever before said platen carriage reaches its latching position to enable said platen carriage to travel the last portion of its movement under momentum.

7. In a platen shifting mechanism, a mounting, a platen carriage movable on said mounting to an upper and lower case position, latching means for holding said platen carriage in its lower case position, spring means for driving said platen carriage to its upper case position, means to release said latching means to enable said platen carriage to move to its upper case position under the influence of said spring means, a pivotable lever in the path of but out of contact with said platen carriage, a second spring means urging said pivotable lever to pivot, holding means for said pivotable lever, and means to release said holding means to enable said pivotable lever to pivot under the influence of said second spring means and contact said platen carriage to drive said platen carriage to its lower case position.

8. In a platen shifting mechanism, a mounting, a platen carriage movable on said mounting to an upper and lower case position, latching means for holding said platen carriage in its lower case position, spring means for driving said platen carriage to its upper case position, means to release said latching means to enable said platen carriage to move to its upper case position under the influence of said spring means, a pivotable lever in the path of but out of contact with said platen carriage, said pivotable lever being associated with said spring means, a second spring means urging said pivotable lever to pivot, holding means for said pivotable lever, means to release said holding means to enable said pivotable lever to pivot under the influence of said second spring means and contact said platen carriage to drive said platen carriage to its lower case position, and means to return said pivotable lever to its original position to reset both of said spring means for further shifting operations.

9. In a platen shifting mechanism, a mounting, a platen carriage movable on said mounting to an upper and lower case position, latching means for holding said platen carriage in its lower case position, spring means for driving said platen carriage to its upper case position, means to release said latching means to enable said platen carriage to move to its upper case position under the influence of said spring means, a pivotable lever in the path of but out of contact with said platen carriage, said pivotable lever being associated with said spring means, a second spring means urging said pivotable lever to pivot, holding means for said pivotable lever, means to release said holding means to enable said pivotable lever to pivot under the influence of said second spring means and contact said platen carriage to drive said platen carriage to its lower case position, a printing bail plunger, resetting means for each of said spring means, and means connected with said bail plunger to actuate said

resetting means to return said pivotable lever to its original position and distend each of said spring means for further shifting operations.

10. In a platen shifting mechanism, a mounting, a platen carriage shiftable on said mounting to an upper and lower case position, means normally out of contact with said platen carriage for moving said platen carriage to one of its case positions, means to actuate said first mentioned means to cause said first mentioned means to contact with said platen carriage and drive it to a case position, and means to stop the actuation of said first mentioned means to cause it to be free from contact with said platen carriage to enable said platen carriage to travel a portion of its movement under momentum.

11. In a platen shifting device, a mounting, a platen movable on said mounting to different operating positions, driving means for driving said carriage to one position, means restraining said driving means from actuation, means to release said restraining means to thereby release said driving means to move said platen to one operating position, a second driving means for driving said carriage to a second operating position, means restraining said second driving means from actuation, means to release said second mentioned restraining means to cause said second driving means to move said platen to a second operating position, means to reset both of said driving means for further shifting operations, a bail plunger having a working and an idle stroke, and means connected with said plunger to operate said resetting means on the idle stroke of said bail plunger.

12. In a shifting mechanism, a frame, a member shiftable on said frame, shifting means to shift said member to one position on said frame, a second independently acting shifting means to shift said member to a second position on said frame, and means to simultaneously condition both of said shifting means for further shifting operations.

13. In a shifting mechanism, a frame, a member shiftable on said frame, spring means to shift

said member to one position on said frame, a second independently acting spring means to shift said member to a second position on said frame, and means to simultaneously condition both of said spring means for further shifting operations.

14. In a platen shifting device, a mounting, a platen movable on said mounting to different operating positions, driving means for driving said platen to one position, a latching lever for preventing the movement of said driving means, a bail plunger, means on said bail plunger also preventing the movement of said driving means while said bail plunger is in its lower position, a pull bar for unlatching said latching lever, means to operate said bail plunger to its upper position, and means to actuate said pull bar to thereby release said driving means to shift said platen to its one position.

15. In a telegraph printer, signal responsive means, power driven means, a platen, platen shift and unshift means comprising individual elongatable springs, means associated with said power driven means to store power in both said springs simultaneously, trigger means individual to said shift and unshift means to retain said shifting means independently in power stored condition, and means controlled by said signal responsive means to operate either of said trigger means to release said respective springs for operation to shift said platen to its other operating position.

16. In a platen shifting mechanism, a mounting, a platen movable on said mounting to different case positions, an elongatable spring associated with said platen for driving said platen to one case position, a second independently acting elongatable spring associated with said platen for driving said platen to its other case position, a single power driven means for conditioning both said springs for operation, and selectable means for separately releasing said springs for driving said platen to its respective case position.
